(57) **CLAIM**

The ornamental design for a fishing lure, as shown and described.

DESCRIPTION

FIG. 1 is a perspective view of a fishing lure;

FIG. 2 is a right side elevational view thereof;

FIG. 3 is a left side elevational view thereof;

FIG. 4 is a top plan view thereof;

FIG. 5 is a bottom plan view thereof;

FIG. 6 is a rear elevational view thereof;

FIG. 7 is a front elevational view thereof;

FIG. 8 is a perspective view of a modified form of the fishing lure;

FIG. 9 is a right side elevational view of the modified form;

FIG. 10 is a left side view of the modified form;

FIG. 11 is a top view of the modified form;

FIG. 12 is a bottom view of the modified form;

FIG. 13 is a rear view thereof;

FIG. 14 is a front view thereof; and,

FIG. 15 is a perspective view of the subject modified form with a diving lip.

The portions shown in broken lines are included for illustrative purposes only and form no part of the claimed design.
